UNITED STATES PATENT OFFICE.

CARL EDWARD WILTON, OF PHILADELPHIA, PENNSYLVANIA.

AUTOMATIC LID-SUPPORT.

1,303,441.

Specification of Letters Patent. Patented May 13, 1919.

Application filed May 10, 1917. Serial No. 187,659.

To all whom it may concern:

Be it known that I, CARL EDWARD WILTON, a citizen of the United States of America, residing at Philadelphia, in the county of 5 Philadelphia and State of Pennsylvania, have invented certain new and useful Improvements in Automatic Lid-Supports, of which the following is a specification.

This invention relates to that class of devices used on such articles as phonograph cabinets for maintaining the top or lid thereof in open position against inadvertent closing. The object of the invention is to produce such a device that is very simple yet 15 positive and dependable in action and a device that may be installed with a minimum of expense.

With these objects in view, the invention consists of the arrangement, construction 20 and combination of parts hereinafter described and particularly pointed out in the claims, it being understood that I do not intend to limit myself to the details of construction nor to the use of the device in connection with phonographs for it may be used 25 on trunks, boxes, etc.

The invention is illustrated in the accompanying drawings in which:

Figure 1 shows a side elevation of my device in place on phonographs;

Fig. 2 shows a perspective view of the bracket and with the cam in place;

Fig. 3 shows a vertical section taken in the plane of the pivot of the cam;

Fig. 4 shows a side elevation of the cam; Fig. 5 is an edge view of the bar and

Fig. 6 is a side view of the same;

Fig. 7 is a view similar to Fig. 1 but with a modified form of the device;

Fig. 8 is a view of the bracket in this modified form;

Figs. 9 and 10 show the different positions the cam of this form assumes;

Fig. 11 shows a side view of the modified bar; and

Fig. 12 an edge view of the same.

In the drawings, the numeral 11 indicates the phonograph case, 12 its top or lid and 13 the support for the phonograph table. 50 14 indicates a bar pivotally carried by a plate 15 secured to the lid 12. Adjacent the free end of the bar 14, a pin 16 is provided. 17 indicates a bracket carried by either the side of the case 11 or the support 13 and is 55 provided with an inclined depending portion 18 circuitously slotted at 19. To this

portion 18 is pivoted a cam 20 having two intersecting slots 21 and 22 in its lower part which unite in an opening or slot 23. The upper part of the cam is inclined and provided with two lugs or fingers 24 and 25 as shown in Fig. 4, which engage the under face of the bracket 17 to limit the movement of the cam. This cam is preferably dished and acted upon by a spring 26 encircling its 60 pivot 27, which spring functions to retard pivotal movement of the cam. 28 represents a recess located in the groove 19 as shown in Fig. 2.

The bar 14 passes through the slot 29 of 70 the bracket 17 and the pin 16 of the bar operates in the slots of the cam and is long enough to extend into the slot 19 when the latter registers with the slots in the cam. A slotted anti-rattling member 50 of suitable 75 material secured to the bracket 17, as illustrated in Fig. 3, prevents marring or rattling of the bar 14. It will be obvious that the bar 14 will pass through the slot 51 and frictionally engage the sides thereof thus 80 being held out of contact with the sides of the slot 19.

In Fig. 1 the device is open and maintained against closing by the engagement of the pin 16 with the lower offset 28 of the slot 85 19. If, however, the lid is desired closed, it is first raised slightly which unseats the pin 16 from the lower offset 28 and raises it upwardly in the slot 21 until it engages the end thereof. Continued movement of the pin 90 until it also engages the end of the upper offset 33 of slot 19 causes the cam to rotate but this in turn has a retarding action upon the movement of pin and bar. The cam moves until the end of the slot 21 registers 95 with the slot 19 so that downward movement and closure of the lid is permitted as the pin moves out of slot 21 past the shoulder 39 and thence out of the slot 19. As the pin passes into slot 19 the cam is caused 100 by the pin to rotate slightly farther bringing the slot 22 also into registry with the slot 19 so that upon opening the lid, the pin 16 will pass upwardly past the central projection 40 on the cam into the slot 22. Continued movement of the pin engages the end 105 of the slot 22 which rotates the cam slightly whereby the exit of the pin out through slot 19 is prevented by the projection 40 and the shoulder 41. Engagement with the end of 110 the slot 21, causes the cam to rotate slightly farther into the position illustrated in Fig.

1, with a consequent retarding action upon further upward movement of the bar and lid. From engagement with the end of the slot 22 the lid and bar are dropped slightly so that the pin moves past shoulder 43 and falls into the offset 28 and the lid is maintained open as described.

In the form shown in Fig. 7 the pin 16' is integral with the bracket 17' while the bar 14' carries the cam 20'. The structure of the cam 20' is quite similar to the cam shown on Sheet 1 with the exception that the lug or fingers 24 and 25' coöperate with a pin 55 on the bar 14' to limit the movement of the cam. The bracket 17' has a slot 29' through which the bar 14' moves.

In Fig. 7 the device is open and maintained against closing by the engagement of the pin 16' with the upper offset 38' of the slot 19', its passage through the slot 19' being blocked by the cam finger as clearly shown. If, however, the lid is desired closed it is first raised slightly which unseats the pin 16' from the offset 38' and causes it to move in the slot 21' until it engages the end thereof. Continued movement of the pin or until it engages the lower end of offset 28' causes the cam to rotate but this in turn has a braking action upon the pin and bar. The cam moves until the end of the slot 21' registers with the slot 19' so that the downward movement and closure of the lid is permitted when the pin moves in slot 21'

and 19'. As the pin passes into the slot 19' the cam is caused by the pin to rotate slightly 35 farther bringing the slot 22' also into registry with the slot 19' so that upon opening the lid, the pin 16' will pass downwardly into slot 22'. Continued movement of the pin engages the end of the slot 22' which 40 rotates the cam with the position shown in full lines in Fig. 7 whereby its exit is prevented. Engagement with the end of the slot has a braking action upon further movement of the bar and lid. From engagement 45 with the end of the slot 22' the lid and bar are dropped slightly so that the pin falls into the recess 28' and the lid is maintained open as described.

What I claim is:

In combination with a hinged cover of a box or the like, a cover support including a bar having one of its ends pivotally connected to the cover, a bracket supported by the box, said bracket having a depending slotted portion, a cam pivotally connected to the depending slotted portion, said cam having slots adapted to register with the slot of the depending portion, and a pin carried by the free end of the pivoted bar for coöperating with the slots of the cam and depending portion of the bracket for supporting the cover in a predetermined position.

In testimony whereof I affix my signature.

CARL EDWARD WILTON.
